UNITED STATES PATENT OFFICE

ROBERT G. CALTON, OF NASHVILLE, TENNESSEE, ASSIGNOR TO TENNESSEE ENAMEL
MANUFACTURING CO., A CORPORATION OF TENNESSEE

REFRIGERATOR

Application filed August 24, 1932. Serial No. 630,278.

This invention relates to refrigerators and, among other objects, aims to provide novel means to confine and control the circulation of air in the food compartment below the ice 5 bunker so that the ice will melt from the bottom and the temperature maintained in the food compartment is dependent on the exposed area of the bottom of the cake instead of its varying superficial area or size. More 10 specifically, the idea is to provide a novel ice rack and associated means constructed and arranged to so control or direct the air circulation in the food compartment that the chilled air is always free to descend without 15 conflicting with the ascending relatively warm air. A further object is to maintain a substantially constant temperature in the food compartment until nearly all of the ice 20 block or cake has melted, thereby producing better refrigeration and avoiding the inconvenience of very frequent ice service.

Other aims and advantages of the invention will appear in the specification when considered in connection with the accompanying drawings, wherein:

Fig. 1 is a vertical sectional view of a simple type of refrigerator embodying one form of the invention;

Fig. 2 is a vertical sectional view taken at right angles to Fig. 1;

Fig. 3 is a top plan view of the ice rack shown in Figs. 1 and 2;

Fig. 4 is a side elevation of the rack;

Fig. 5 is a vertical sectional view of a refrigerator embodying a greatly simplified form of the invention;

Fig. 6 is a vertical sectional view taken at right angles to Fig. 5;

Fig. 7 is a top plan view of the ice rack shown in Fig. 5; and

Fig. 8 is a side elevation of the rack.

In the ordinary type of refrigerator, the circulating air passes through the ice compartment and is cooled or chilled by contact with the cake of ice. Naturally, a large block or cake of ice maintains a lower temperature in the food compartment than a small cake due to the fact that the large cake presents a much greater cooling surface.

When the size of the cake is reduced to about half, the temperature in the food compartment is higher than the refrigerating temperature required properly to keep certain foods. Moreover, the chilled air cannot descend freely from the ice bunker because it is retarded by rising currents of warm air. It is very important that the air shall circulate freely to maintain a constant temperature in the food compartment. Heretofore, very frequent ice service has been necessary, and this has resulted in waste, because partially consumed pieces of ice are either thrown out or make it impossible for the ice man to put in a capacity-sized cake. Moreover, some inconvenience is entailed every time ice is added, because the ice compartment has to be cleared of all stored food. This invention provides an improved, relatively simple and efficient ice rack having associated means to direct the air circulation and insure a substantially constant temperature in the food compartment until practically all of the ice has melted. Moreover, it avoids the necessity of replenishing the ice before it has melted, making possible far less frequent servicing and the inconvenience incident thereto.

Referring to Figs. 1 to 4, one form of improved rack is shown in an upright refrigerator 10 having a double-walled, insulated drip pan 11 which forms the bottom of the ice bunker or compartment. The drip pan is shown as being spaced from the side walls of the refrigerator and has the usual rectangular opening 12 in the center to permit chilled air to descend through it into the food compartment.

This form of ice rack has a top plate 13 made of a reinforced, rectangular sheet of metal closely fitted in the refrigerator casing and supported on the drip pan by means of U-shaped legs 14 conveniently formed of bent strips of sheet metal brazed or soldered to the bottom of the top plate at its front and rear edges. It will be noted that circulating air cannot enter the ice bunker or compartment around the edges of the rack.

In Fig. 3, the rack is shown as having a rec-

tangular opening 15 above the air circulating opening 12 in the drip pan. On the lower surface of the drip pan there is shown a plurality of parallel fins 16 conveniently made of sheet metal having upper flanges 17 brazed or soldered to the top plate. These fins provide heat exchanging or conducting elements to chill the air circulating through them. They extend transversely of the refrigerator and terminate short of the side walls so as to provide transverse flues or passages for the circulating air. The arrangement is such as to control or direct the circulating air in separate streams rising at the opposite sides of the food compartment, being accelerated by absorption of heat conducted through the side walls of the casing. The chilled currents merge and descend freely through the opening 12. In Fig. 1, the full line arrows indicate the general paths of the air currents.

Referring to Figs. 1 and 3, the fins extend across the opening 15 in the rack and their upper flanges 17 provide reinforced, spaced supports for that portion of the cake of ice above the opening 15. Below the opening 15, the fins are shown as being cut away so that each one presents an M-shaped notch 18. Within these notches and below the opposite side edges of the opening 15, a pair of inclined deflector plates 19 is suitably secured. As shown in Fig. 1, these deflector plates drain the water downwardly and inwardly toward each other, their outer edges being preferably brazed or soldered to the edges of the notched fins at a substantial distance below their upper edges or the bottom of the rack. Their lower edges are spaced apart a sufficient distance to permit air to circulate between them. These deflectors serve to drain the water which drips through the opening 15 into a double, insulated drip trough or pan 20 supported by U-shaped brackets 21 which are secured to the bottoms of the deflector plates. The trough 20 drains the water to the back side of the drip pan 11 from which it passes into the usual drain tube 22.

Assuming that a block of ice 1 is placed in the ice bunker and substantially covers the rack, the circulating air will follow substantially the paths indicated by the full-line arrows in Fig. 1, the right and left hand ends of the fins or heat exchanging elements 16 serving to chill the air as it passes through the flues formed by the fins. The chilled streams are deflected downwardly and inwardly by the lower faces of the deflectors. Circulation will continue to follow the direction of the full-line arrows as long as the bottom of the ice cake contacts with the imperforate portions of the top plate 10 of the rack. As long as the ice cake remains in contact with the top plate, practically none

of the air will come in contact with the bottom of the ice immediately above the opening 15, because it descends rapidly upon being chilled.

When the ice melts immediately above the rack and assumes the shape roughly indicated by the dotted lines in Fig. 1, it no longer contacts with the ice rack at the opposite sides of the opening 15. Hence, the chilling effect of the fins at their ends is greatly diminished. The air must be chilled before it will descend through the circulating opening 12 and it therefore follows the paths of the dotted arrows in Fig. 1, passing between the outer or upper edges of the deflectors 19 and the bottom of the top plate 10. The V-shaped portions of the fins formed by the M-shaped notches then serve to chill the air conducting the heat to the central portion of the bottom of the ice. Moreover, some of the air comes in direct contact with the ice between the flanges 17 of the fins. Thus, the circulating air melts away the ice cake above the opening 15 until the ice cake again rests flatly on the top plate at the opposite sides. The air circulation will again follow the directions of the full-line arrows, and the process is repeated until the ice is completely melted.

In Figs. 5 to 8 inclusive, there is shown a greatly simplified form of rack also closely fitted in an upright refrigerator 10' having a double drip pan 11' and the drip pan, likewise, presents a central air circulating opening 12'. In this instance, the top of the rack is made of two spaced rectangular pieces of sheet metal 23 shown as being spot-welded to the webs of a plurality of channel-shaped, sheet metal fins 24 extending across the refrigerator casing. The rack is shown as being supported on pairs of strap metal legs 25 each bent U-shaped and extending across the tops of the channel-shaped fins 24 at their ends, each of the fins being welded or otherwise secured to horizontal portions of the legs. Hence, the legs serve to reinforce the whole rack and to support the lower edges of the fins above the upper edges of the drip pan.

Referring to Figs. 5 and 7, it will be noted that the fins 24 serve as supports for the ice cake between the two plates and the bottom of the ice is partially exposed to the circulating air between the fins.

The rectangular opening between the spaced top plates 23 is directly above the central air opening 12 in the drip pan and some water drips through both openings. In Figs. 5 and 6, there is shown a small double-walled auxiliary drip pan 26 suspended on hangers or brackets 27 below the drip pan 11' and arranged to drain to the rear of the casing, being connected to the drain pipe 22. The main drip pan is shown as having a short

drain nipple 28 above the open upper end of the drain pipe.

The simplified form of rack also directs the air circulation in two separate paths as indicated generally by the arrows in Fig. 5. The rising currents or streams are accelerated by absorbing some heat conducted through the side walls of the casing and are guided inwardly under the rack by the fins. Both streams of air are chilled by conduction through the fins and by direct contact with the bottom of the ice cake in the middle of the rack. Since the ice is partially exposed at the mid-portion to the initially chilled air currents coming from the sides, it will melt substantially uniformly throughout its bottom surface.

The efficiency of the refrigerator shown in Figs. 5 and 6 is somewhat greater than that shown in Figs. 1 and 2, because the circulating air is chilled by contact with the entire surface of fins and the exposed bottom portion of the ice cake. Moreover, the simple form of rack is much easier to manufacture.

From the foregoing description, it will be seen that both forms of the improved ice rack are very simple in design and efficient in operation. The fins serve to regulate the temperature in the food compartment automatically and independently of the diminishing size or volume of ice in the ice bunker or compartment. Moreover, they insure rapid circulation of chilled air through the food compartment. Actual tests have demonstrated that the frequency of ice service is greatly reduced, and that substantially the same temperature is maintained in the food compartment at all times. This eliminates considerable waste of pieces of ice which are of irregular shape when refrigerators of the ordinary type are serviced. It reduces the overhead of the ice man because he can deliver a cake of ice of capacity size every time service is required, without having to stop and chip off pieces to make it fit.

Obviously, the present invention is not restricted to the particular embodiments thereof herein shown and described. Moreover, it is not indispensable that all the features of the invention be used conjointly, since they may be employed advantageously in various combinations and sub-combinations.

What is claimed is:

1. In a refrigerator of the class described, an ice bunker having a drip pan spaced from the opposite side walls of the refrigerator casing and having an air circulating opening in the middle; a metal ice rack mounted on the drip pan and closely fitting the inside of the casing; and a series of parallel heat conducting fins on the rack extending transversely of the casing from one side wall to the other and providing flues to direct the air circulating in the food compartment below the

rack and, thence, downwardly through said circulating opening in the drip pan.

2. In a refrigerator of the class described, a drip pan having its opposite edges spaced from the opposite side walls of the refrigerator casing; a central air circulating opening therein; a metal ice rack closely fitted in the casing and having legs supporting it on the drip pan; a series of metal fins depending below and forming a part of the ice rack and extending across the refrigerator to provide heat exchanging elements which chill the air in the food compartment, said fins directing the air to circulate in separate paths which merge below the central portion of the rack and descend freely through the air circulating opening in the drip pan.

3. In a refrigerator of the class described, an ice bunker or compartment having a drip pan spaced from the opposite side walls of the refrigerator casing; a metal ice rack mounted on the drip pan and closely fitting the inside of the casing to prevent circulating air from entering the ice compartment; a series of parallel heat conducting fins extending transversely of the casing and secured to the bottom of the rack providing fins to direct the air circulating in the food compartment; and a pair of inclined deflector plates secured to the fins below the central portion of the rack and arranged to control the circulation of air so that an ice cake on the rack will melt substantially uniformly from the bottom.

4. In a refrigerator, an ice rack supported on the bottom of the ice bunker and fitting therein to prevent circulating air from entering the ice compartment; heat conducting elements on the bottom of the ice rack connected to direct the air to circulate in two paths which merge below the middle of the rack as the chilled air descends; and spaced deflectors secured to the heat conducting elements below the central portion of the rack arranged to direct the currents of circulating air alternately under opposite sides and under the central portion of the rack, whereby to melt the ice substantially uniformly and maintain a substantially constant temperature in the food compartment until the ice is practically consumed.

5. In a refrigerator of the class described, a drip pan spaced from the inside walls of the refrigerator and having a central, air-circulating opening; a substantially rectangular ice rack made of sheet metal also having a central opening; a plurality of vertical, sheet metal fins secured to the bottom of the rack and extending transversely of the refrigerator to provide horizontal air-circulating flues to direct the air circulation in the food compartment; said fins having substantially M-shaped notches below the opening in the rack and their upper edges near the middle, providing supports for an ice cake; a

pair of spaced, inclined deflector plates secured in said notches at their opposite edges to drain the water which falls through the opening in the rack; and a drip trough secured to the deflector plates to drain the water into the drip pan; said deflector plates also acting as baffles automatically to divert the chilled, circulating air downwardly into the air-circulating opening in the drip pan

10 when the ice is in contact with the top of the rack at its opposite sides and their upper edges being spaced below the bottom of the rack to permit the circulating air to enter the space above the deflector plates and be

15 chilled by the mid-portion of the ice cake after it has melted out of contact with the sides of the rack, whereby to level off the bottom of the ice so that the cycle of circulation is repeated until the ice is practically consumed.

6. In a refrigerator of the character described, a drip pan dividing the refrigerating casing into a food compartment and ice bunker and having its opposite side edges spaced

20 from the opposite side walls of the refrigerator casing; said drip pan having a central air-circulating opening therein; an ice rack supported on said drip pan and having spaced plates at opposite sides of the ice compartment leaving a substantially rectangular opening above the air-circulating opening in the drip pan; a plurality of depending parallel metal fins of substantial area secured to the bottoms of the spaced plates and extending transversely of the refrigerator casing from one side wall to the other so as to direct circulating air in separate streams which rise along the side walls of the refrigerator casing and merge after the air is

25 chilled and descends through said air-circulating opening in the drip pan; and an auxiliary drip pan suspended from the rack and

supported above the opening in said first-named drip pan to catch the water which drips through the central opening in the ice rack without interfering with the free circulation of chilled air passing through the main drip pan.

7. As an article of manufacture, an ice rack for top icer refrigerators comprising a sheet metal top having a central rectangular opening; a plurality of parallel sheet metal fins depending from and welded to the bottom of said sheet metal top and extending across said opening, said sheet metal fins being of substantial width and area to constitute reinforcing and heat exchanging elements; and supporting legs for the rack extending below the lower edges of said fins adapted to support the rack on a drip pan.

8. As an article of manufacture, an ice rack for refrigerators comprising a sheet metal top having a central rectangular opening; and a plurality of parallel sheet metal fins depending from the bottom wall of the sheet metal top and extending across said opening constituting reinforcing and heat exchanging elements, each of said fins having a substantial heat exchanging area at its ends and a relatively smaller area intermediate its ends below said central opening. 90

9. As an article of manufacture, an ice rack comprising a pair of strap metal supports each having bent legs at its ends; a plurality of parallel, channel shaped sheet metal elements each connected at its ends to said strap metal supports and depending from their lower faces; and a pair of spaced rectangular top plates secured to the webs of said channel shaped elements adjacent to said strap metal supports. 95

In testimony that I claim the foregoing as my own, I have hereto affixed my signature.

ROBERT G. CALTON.
